LESTER A. GRIMES, OF ORANGE, NEW JERSEY.

LINK FOR SPRINKLER-HEADS.

1,209,574.

Specification of Letters Patent. Patented Dec. 19, 1916.

Application filed July 5, 1916. Serial No. 107,534

To all whom it may concern:

Be it known that I, LESTER A. GRIMES, a citizen of the United States, and a resident of Orange, in the county of Essex and State 5 of New Jersey, have invented a new and Improved Link for Sprinkler-Heads, of which the following is a full, clear, and exact description.

This invention relates to automatic sprinklers and has particular reference to tension links to hold the compression members from collapsing under normal usage.

More definitely stated, the primary object of this invention is to simplify, cheapen and 15 correspondingly increase the efficiency and reliability of links of this character, each link including a pair of duplicate plates normally held rigidly together by means of fusible metal.

With the foregoing and other objects in view the invention consists in the arrangement and combination of parts hereinafter described and claimed, and while the invention is not restricted to the exact details of 25 construction disclosed or suggested herein, still for the purpose of illustrating a practical embodiment thereof reference is had to the accompanying drawings, in which like reference characters designate the same parts 30 in the several views, and in which—

Figure 1 is a front elevation of a standard form of sprinkler head having my improved link in connection therewith; Fig. 2 is a vertical sectional view of the same on the line 35 2—2; Fig. 3 is an enlarged vertical sectional detail showing the link assembled for the purpose of resisting maximum strain; Fig. 4 is a perspective view of one of the plates; and Fig. 5 is a view of the same character 40 as Fig. 3, but showing the plates assembled so as to resist less strain than in Fig. 3.

This invention comprises a link consisting of two parts or plates preferably made as duplicates for the sake of cheapness of construction and reliability of assemblage and adapted to be secured together by fusible metal indicated at 10. Each plate is preferably of the form shown in Fig. 4, being provided with a hole 11 at one end and a cutaway 12 at the other end. Otherwise the plate is imperforate throughout. The main portion of the plate is flat, but is so formed at different points as to include a plurality of depressions forming a like number of 50 lugs or projections on the opposite side, the metal throughout the plate and the several

depressed portions being practically of uniform thickness. Two of these depressions are formed at the end on opposite sides of the eye 11, thereby producing lugs 13, which in the preferred manner of assemblage are adapted to project into sockets 14 on opposite sides of the cutaway 12 of the other plate. These projections 13 and coöperating sockets 14 of the two connected plates may 60 be regarded as centering devices, while adjacent the center of each plate are formed oppositely directed sockets 15 and 16, producing projections 17 and 18, the socket 15 of each plate being adapted to receive the 70 projection 18 of the other plate when assembled as shown in Fig. 3, while as indicated in Fig. 5, the plates may be assembled so that the depression 16 of either plate will receive the projection 17 of the other. These 75 sockets or depressions and the corresponding projections are indicated as of the form of spherical segments and they are so formed also that the plates may be assembled in either way, as shown in Fig. 3 or 80 Fig. 5. The coöperating sockets and projections in either case, however, provide that the flat portions of the plates are sufficiently spaced from each other to receive a layer of fusible metal 10. Said fusible metal in 85 practice is extended all the way around the joint or meeting line between adjacent plates, but the metal does not lie between the coöperating curved portions of the plates.

In further comparison of Figs. 3 and 5, it 90 will be noted that in the preferred manner of assemblage of Fig. 3, the tension or strain applied to the eye portions of the plates, tending to move them apart, will be resisted, so far as direct contact between the middle 95 of the two plates is concerned, by about double the amount of offset. In other words, to cause the separation of the two plates, the crest of each projection 18 must glide from the bottom of its socket 15 up and over the 100 similar crest of the other plate, whereas in Fig. 5, a similar separation would be effected simply by the gliding of the one plate over the other far enough for the crest of one projection 17 to draw out of its socket 16. 105 Under certain conditions, the arrangement of Fig. 3 is preferable to that of Fig. 5, while in other specifications or under other conditions, the arrangement of Fig. 5 may be preferred. In either event, the link 110 plates are customarily stamped on their outer faces to indicate the date of assem-

blage of the link or the melting point of its solder, so that it is impossible for the link plates to be erroneously assembled.

With the foregoing specific description of the link, its manner of operation may be briefly set forth in connection with the diagrams of Figs. 1 and 2. The sprinkler head H comprises a compression portion C and a pair of toggle arms T having hooks engaging in the eyes 11 of the link. When the sprinkler head is set up, as indicated, it is tested and sufficient tension is exerted upon the link to insure the prompt and complete separation of the link plates and collapsing 15 of the toggle links T when sufficient heat is generated to melt the solder or fusible metal 10. When the solder begins to melt, the co-operation of the crests and sockets at the center of the link will cause the links to 20 separate with a combined sliding and bodily movement.

As will be plainly seen from Figs. 3 and 5, the interlocking portions at the center of the plates provided by the continuous compound 25 curves lie in direct contact with each other. In other words, the effect of the solder between the flat portions of these plates is that of holding the two plates from bodily separation, and therefore the strain to which the 30 link is ordinarily subjected, tending to part the plates with a gliding movement one over the other, is directly resisted by the co-operating projections 18 and 18 abutting directly

against each other, as shown in Fig. 3. It is well known in this art that the constant 35 strain on a fusible metal link of this character incident to the normal use of the device is very great, and if such strain is borne directly by the solder, which is necessarily soft to serve its purpose, there is a tendency 40 to what is known as "cold flow" and a likelihood of premature collapse of the sprinkler head. It will be appreciated therefore that with the two projections 18 and 18 in direct contact, the tendency for the plates to 45 slip or creep one over the other will be resisted by the hard metal of the plates, rather than by the soft solder surrounding the interlocking features. The same principle applies also to Fig. 5, but in the latter figure, 50 the plates will separate more easily than in Fig. 3.

I claim:

In a link for automatic sprinkler heads, the combination of a pair of duplicate plates 55 substantially flat throughout their main portions, each provided with projections and sockets of the form of hemi-spherical segments, one of said sockets merging into an adjacent projection in a continuous compound curve, all of the compound curved surface of one plate fitting directly against a similar surface of the other plate, and fusible metal connecting the flat portion of one plate to the flat portion of the other.

LESTER A. GRIMES.
